(57) CLAIM

The ornamental design for a fruit and vegetable processor, as shown and described.

DESCRIPTION

FIG. 1 is a perspective view of a fruit and vegetable processor showing my new design;

FIG. 2 is a front side elevational view thereof;

FIG. 3 is rear side elevational view thereof;

FIG. 4 is a left elevational view thereof;

FIG. 5 is a right elevational view thereof;

FIG. 6 is a top plan view thereof;

FIG. 7 is a bottom plan view thereof; and,

FIG. 8 is another perspective view thereof, with a capped flat cover engaged.

The dotted line showing of the capped flat cover is for illustrative purposes only and forms no part of the claimed design.

The portions shown in broken lines form no part of the claimed design.
